UNITED STATES PATENT OFFICE

2,641,805

WINDOW FRAME TEAR-OFF FLANGE

Sam Spector, Shaker Heights, and George J. Teplanszki, Warrensville Heights, Ohio, assignors to Tilt-Type Products, Inc., Cleveland, Ohio, a corporation of Ohio

Application December 21, 1951, Serial No. 262,737

2 Claims. (Cl. 20—55)

1

This invention relates to improvements in storm window frame construction and is particularly adapted for use in storm window frames of the "self-storing" type which receive an upper glazed sash and a sliding lower glazed sash which may be raised or "stored" during the summer-time to provide an opening in the lower half of the storm window frame; this opening may be screened with a sliding screened sash, which is adapted to be raised or "stored" during the winter-time, when the lower glazed sash is in use. This application is a continuation-in-part application with respect to our co-pending application Serial No. 85,746 for Storm Window, filed April 6, 1949, now U. S. Patent No. 2,629,143 issued February 24, 1953 and with respect to our co-pending application Serial No. 144,386 for Storm Window, filed September 7, 1949, now U. S. Patent No. 2,595,016 issued April 29, 1952.

It is an advantage of storm window frames made according to our invention that they may be made of extruded metal, preferably aluminum or stainless steel, having channel or box sections, thereby providing the permanence and strength of metal while being light-weight for shipping and handling and economical to produce. Storm windows made according to our invention are closely fitting, and may be produced for closer tolerances than has been heretofore possible with wood or metal storm windows of the "self-storing" type.

Because of the close fits necessary to obtain the desirable wind-tightness in storm windows, the so-called self-storing storm windows heretofore available have not satisfied this need. Such failure has been attributable largely to the fact that the prior art storm windows have had to be "custom built," i. e., made on special order and fitted on the job in order to compensate or correct for the inevitable warped, misaligned and/or out-of-plumb construction inevitably found in the casings of primary windows in wood or masonry buildings. The carpentry or tinsmith work involved in fitting prior art wood or metal storm windows not only was very expensive but could not equal the close-tolerance precision construction of our windows. Our storm window frames may be either cut and built to stock sizes in the factory or cut in the factory, shipped, knocked-down, and assembled on or near the site of installation. Though our storm window frames are preferably produced in stock sizes, such stock-size frames may be easily fitted to the wood or masonry casing of a primary window, despite the variations normal-

2

ly found in such window casings. This substantial advantage is obtained by providing an integral "waste strip" or flange around the outside of our storm window frames.

5 Other advantages of this invention will be apparent from examination of the following specification and the drawings in which:

Figure 1 is an outside front elevation of a storm window frame made according to our invention.

10 Figure 2 is a side elevation of the structure shown in Figure 1.

Figure 3 is an enlarged sectional detail of the sill construction taken on the line 3—3 of Figure 1.

15 Figure 4 is an enlarged sectional detail of the frame jamb, taken along the line 4—4 of Figure 1.

Figure 5 is an enlarged sectional view of the frame lintel taken along the line 5—5 of Figure 1.

20 Referring to the drawings, in which like reference characters refer to like parts, our storm window frame is referred to generally by the reference character 10. The frame is comprised of a channeled lintel member 11, channeled jamb members 12 and 13, and a sill member 14, all being preferably formed of channels of stainless steel or like corrosion-resistant metal to provide the strong and rigid box or channel sections disclosed in the several detail views and discussed below. Although the frame members 11, 12, 13 and 14 are of a complex cross-section, they are formed economically and accurately either by the extrusion of molten aluminum or like metal through suitable extrusion dies or by rolling the section from coiled steel strip. Long lengths of such extruded stock may be cut to window lengths.

Specifically, the lintel 11 is cut to the window width required from standard deep channeled stock of the cross-section shown in Figure 5 of the drawings. Such lintel stock comprises, in cross-section, a body portion 110 having sash receiving channels 111, 112, and 113 and an integral, outwardly extending flange or "waste-strip" 114 provided with the parallel break-off grooves 115. In the particular embodiment shown, the ends of the window lengths of the lintel stock are suitably mitered to form the mitered joints with the jambs 12 and 13, as shown. The jambs 12 and 13 are formed from lengths of standard stock of similar cross-section, the cross-section of the jamb 12 being illustrated in Figure 4. Each jamb may comprise a box section 120 having sash receiving channels 121, 122 and 123 (corresponding to the lintel

channels 111, 112 and 113 and an integral flange of "waste strip" 124 provided with parallel break-off grooves 125.

It should be noted that the waste strip 124 of the jambs 12 and 13 occupies the same relative position with respect to its sash receiving channels as the waste strip 114 of the lintel 11 occupies with respect to its sash-receiving channels, so that, when the lintel 11 and jambs 12 and 13 are joined with their respective sash-receiving channels in alignment, the waste strips 124 and 114 will form a continuous grooved fin around the top and sides of the frame 10.

As may be seen in Figure 3, the sill 24 may comprise a length of extruded stock having a substantially box section and comprised of a sill portion 240 which may have a bevelled sealing ridge 241 which, with the ridge 242, defines a screen sash receiving channel 243. The sill portion carries a dependent sealing fin 244 and a seating fin 245.

As a final assembly operation, the sill 14 is joined to the jambs 12 and 13. The sill 14 comprises a hollow body or box portion 140 having a slot adapted to receive a rubber sealing strip 141 which engages the seating fin 245. The body portion 140 carries a sealing fin 142 which is engaged by the fin 244 of the sill 24. The body portion 140 also carries the integral waste strip 144 provided with break-off grooves 145. The length of the extruded stock from which the sill 14 is cut is milled at the ends to permit the body portion 140 to be received between the jambs 12 and 13 and the waste strip 144 is notched, as shown in Fig. 1, to receive the ends of the jambs 12 and 13. The notches in the thin waste strip 144 are easily trimmed, as by filing, to compensate for any accumulation of manufacturing tolerance and to permit the sill 14 to seat firmly on the seating fin 245 of the sill 24.

Storm window frames constructed and assembled as above described are preferably made up in stock sizes to carry sashes of the approximate width of the sashes of the primary window on which the frame is to be mounted. The proportions of the several waste strips 124 are then such that their total width will exceed the width of the opening between the casing jambs in any primary window casings. The height of a storm window is also selected so that the waste strips 114 and 144 will exceed the height of the opening between the sill and the lintel of the primary window casing. To fit the storm window, all that need be done is to break off the waste strips along the break-off grooves 115, 125 and 145 until the waste strips fit against the blind stops of the casing, the ends of the sill waste strip 144 being trimmed as necessary. The waste strips are then drilled and screwed to the casing.

While we have disclosed a preferred and tested embodiment of our storm window frame, it is understood that other specific embodiments may be fabricated without departing from the scope

of our invention as defined in the following claims.

What is claimed is:

1. The method of installing a stock size storm window frame within a primary window having arbitrary dimensions without distorting and mis-aligning said stock size storm window frame comprising the steps of providing a stock size storm window frame including jamb frame members and transverse frame members at least one of said jamb frame members and one of said transverse frame members being bordered by integral flat coplanar flanges grooved on one surface along longitudinal parallel lines and the surfaces of said co-planar flanges on the reverse side from said one surface being substantially planar to define outwardly of the innermost of said lines associated with each frame member, a tear-off flange comprised of a plurality of tear-off strips, discarding the number of said tear-off strips necessary to accommodate the height and width of said storm window frame to the dimensions of said primary window, and thereupon anchoring said flat coplanar flanges to said primary window.

2. The method of installing a stock size storm window frame within a primary window having arbitrary dimensions without distorting and mis-aligning said stock size storm window frame comprising the steps of providing a stock size storm window frame including jamb frame members and transverse frame members at least one of said jamb frame members and one of said transverse frame members being bordered by integral flat co-planar flanges grooved on one surface along longitudinal parallel lines to progressively shallower depths from the outermost to the innermost of said lines associated with each frame member and the surfaces of said co-planar flanges on the reverse side from said one surface being substantially planar to define outwardly of the innermost of said lines associated with each frame member, a tear-off flange comprised of a plurality of tear-off strips, discarding the number of said tear-off strips necessary to accommodate the height and width of said storm window frame to the dimensions of said primary window, and thereupon anchoring said flat co-planar flanges to said primary window.

SAM SPECTOR.
GEORGE J. TEPLANSZKI.
